CLAIM

The ornamental design for a wearable device, as shown and described.

DESCRIPTION

FIG. 1 is a back-left-perspective view of a first embodiment of a wearable device;

FIG. 2 is a back view thereof;

FIG. 3 is a front view thereof;

FIG. 4 is a left-side view thereof;

FIG. 5 is a right-side view thereof;

FIG. 6 is a top view thereof;

FIG. 7 is a bottom view thereof;

FIG. 8 is a back-left perspective view thereof, in an alternate operating condition with a computing component of the wearable device shown removed from a frame of the device;

FIG. 9 is a left-side view thereof;

FIG. 10 is a top-right-perspective view of the computing component of the wearable device shown isolated from the wearable portion of the wearable device;

FIG. 11 is a top view thereof;

FIG. 12 is a bottom view thereof;

FIG. 13 is a right-side view thereof;

FIG. 14 is a left-side view thereof;

FIG. 15 is a back view thereof; and,

FIG. 16 is a front view thereof.

The dot-dash broken lines define the bounds of the claimed design. The dot-dot broken lines depict portions of the wearable device. The broken lines form no part of the claimed design. It is to be understood that, in the case of dot-dash boundary lines, the claimed design extends to but does not include the defined boundary.
